UNITED STATES PATENT OFFICE.

JOHN C. COOMBS, OF MIDLAND PARK, NEW JERSEY.

REED CONSTRUCTION FOR LOOMS.

1,146,478.

Specification of Letters Patent. Patented July 13, 1915.

Application filed September 23, 1913. Serial No. 791,344.

To all whom it may concern:

Be it known that I, JOHN C. COOMBS, citizen of the United States, residing at Midland Park, in the county of Bergen and State of New Jersey, have invented certain new and useful Improvements in Reed Constructions for Looms, of which the following is a specification.

This invention relates to an improvement 10 in reed constructions for looms.

The primary object of the invention is to provide a reed in which the "dents" are so arranged as to reduce friction, whereby free movement of the warp threads through the 15 reed will be permitted, and in which knots or enlargements in the thread will pass between the "dents."

A further object of the invention is to provide a structure in which the dents may 20 be readily positioned within the reed frame and properly spaced from each other without accurate adjustment.

A further object of the invention is to provide a structure in which one set of dents 25 are arranged in advance of the other, the dents of one set being disposed in staggered relation with respect to the dents of the other set, and in which the dents on each side present a smooth and unobstructed surface.

For a full understanding of the invention 30 reference is to be had to the following description and accompanying drawing, in which:—

Figure 1 is a perspective view of a portion 35 of the reed. Fig. 2 a section on the line 2—2 of Fig. 1. Fig. 3 a view showing a modified form of frame. Fig. 4 a section on the line 4—4 of Fig. 3. Fig. 5 a detail view of a portion of the spacing frame shown 40 in Fig. 3.

Corresponding and like parts are referred to in the following description and indicated in all the views of the accompanying drawings by the same reference characters.

Broadly the present invention contemplates the provision of a reed structure in which the dents are disposed in staggered relation, that is, two rows of dents are supported by the frame and are so arranged 45 that a dent of one row will be disposed immediately between and in the rear of the

dents of the other row, the reed when viewed in end elevation presenting spaced parallel dents.

It is well-known in the art that where the 55 dents are arranged in perfect alinement, the frictional contact of the thread with the same impedes the progress of the warp and occasions breakage when knots or enlargements occur in the thread.

The present invention is designed to provide a structure in which the threads will be held as close to one another as where the dents are arranged in alinement, and yet which will at the same time allow them to 65 readily pass between the dents. This cannot be accomplished by merely spacing the dents, as to do this would prevent the use of such reeds in "beating up" fine fabrics.

In the drawings, 10 designates the frame 70 which consists of the longitudinally disposed bars 11 and 12 arranged in pairs, one of the pairs of bars constituting the base of the frame and the other pair of bars forming the top of the frame. The ends of the 75 frame are formed by vertically extending spaced bars 13 and 14 which have their terminals disposed between the longitudinal bars 11 and 12. The dents are arranged in two rows 15 and 16 which extend longitudinally of the reed frame, one row being 80 arranged in advance of the other.

In the form shown in Figs. 1 and 2, the front row of dents is spaced from the rear 85 row by longitudinal bars 17 and 18 which are disposed parallel with the spaced longitudinal bars 11 and 12 of the frame. These bars 17 and 18 are placed between the rows, the edges of the dents contacting with the bars. A strip of soft metal 19 is arranged 90 on each side of each of the bars 17 and 18 and is disposed parallel therewith, the strips contacting with the faces 20 of the vertical bars 13 and 14. The dents are spaced longitudinally of the reed frame at its upper 95 and lower edges by coiled springs 21 which embrace the soft metal strips 19 and the spacing bars 17 and 18, the convolutions of said springs being disposed between the dents.

It will be understood that the wire from 100 which the springs are formed is of the same

thickness throughout the entire length of the spring, and in this manner the reeds of the front and rear section will be spaced the same distance apart throughout the entire length of the reed frame. As is usual in constructions of this character in which a coil spring is used as a spacing means, the springs after being positioned between the dents have their convolutions permanently spaced by pouring solder between the same, whereby the permanent spacing of the dents is attained.

It will be noted, particular reference being had to Fig. 4 of the drawing, that the dents are spaced the same distance longitudinally of the frame as though they were side by side, and thus the fabric will be "beaten up" as effectually as with the usual form of reed. It will be seen, however, that the thread has free passage between the dents and that "bunches" or knots in the thread may pass freely between the same without danger of breakage and without binding. Thus the construction not only permits rapid movement of the warp, but it also prevents breakage, often times occasioned by irregularities in the thread or yarn.

The many advantages of a construction of this character will be clearly apparent, as it will be noted that the same may be easily and economically manufactured, as the dents may be more conveniently assembled than when placed in alinement with each other. It will also be seen that in use the structure is as effectual in the "beating up" of the fabric as is the usual form of reed, the present structure, however, operating without friction or danger of breakage when "bunches" or knots occur in the thread or yarn.

In the form shown in Fig. 3, the frame consists of the upper and lower bars 22 and 23, the ends of which are recessed as at 24. A spacing frame 25 is supported by the bars 22 and 23. This frame consists of vertically extending side members 26 which constitute the end bars of the reed frame and the longitudinally extending bars 27 and 28, the bars 26 extending beyond the bars 27 and 28, their terminals 29 being inserted within the recesses 24 formed in the bars 22 and 23 and soldered to said bars. While solder has been illustrated as the securing means, it will be noted that fastening devices may be passed through the corners of the frame, whereby the spacing frame will be rigidly secured to the longitudinally disposed bars 22 and 23. The longitudinal bars are formed of soft metal and their inner faces 30 are recessed to receive the terminals of the dents. In this form the dents are arranged in spaced rows, the dents of one row being disposed in staggered

relation to the dents of the other row, the 65 longitudinal bars 27 and 28 of the spacing frame 29 maintaining the rows in spaced relation in the same manner as the bars 17 and 18 in the form shown in Fig. 1. The bars 22 and 23 are reduced in thickness adjacent their inner edges and strips 32 of soft metal which are disposed parallel with the longitudinal bars 27 and 28 of the frame 25 are supported on said reduced portions. In this form the coiled springs embrace the 75 strips 32 and the bars 27 and 28 and thereby maintain the dents in spaced relation.

It will also be noted that the structure may be as readily positioned on the loom as the usual reed and that its use will not 80 necessitate any change whatsoever in the arrangement of the race or the lay-beam, the reed frame construction being practically the same as in those reeds which are now in use, so far as its action with respect 85 to the shuttle is concerned.

What I claim is:—

1. A reed construction for looms comprising a rectangular frame including upper and lower spaced bars, upper and lower 90 intermediate spacing bars, front and rear dents having a staggered arrangement and disposed with their end portions inserted between the spaced and the intermediate spacing bars, and means for connecting the 95 spaced and intermediate bars and confining the dents between them.

2. A reed construction comprising front and rear dents having a staggered arrangement, spacing bars arranged between end 100 portions of the dents, other bars exterior to the dents and opposite the spacing bars and at the sides thereof, and wire coils connecting the exterior and spacing bars and confining the dents therebetween and serving 105 as spacing means for the dents.

3. A reed construction for looms comprising a frame including longitudinal bars, the ends of said bars being recessed, a spacing frame formed with longitudinal bars and 110 vertical bars, the vertical bars extending beyond the longitudinal bars and being received within the recesses formed in the first mentioned longitudinal bars, dents disposed in spaced rows and having their terminals extending within recesses formed in the longitudinal bars, and coiled springs embracing the longitudinal bars of the spacing frame, the convolutions of said coiled springs spacing the dents longitudinally of 115 the frame.

4. A reed construction for looms comprising a frame including longitudinal bars formed at their ends with recesses, a spacing frame including vertically extending 125 portions, the terminals of which are inserted within the recesses formed in the longitudinal bars, the spacing frame being pro-

vided with longitudinal portions, dents ar-
ranged in rows on each side of the spacing
frame and having their terminals received
within the recesses formed in the longitudi-
5 nal bars, and means for spacing said dents
longitudinally of the frame.

In testimony whereof I affix my signature
in presence of two witnesses.

JOHN C. COOMBS.
